UNITED STATES PATENT OFFICE

CHARLES SHRIVER, OF MASSILLON, OHIO

PICKLING TANK

Application filed September 23, 1931. Serial No. 564,531.

This invention relates broadly to apparatus for pickling metal sheets, strips, and the like, and it has for its primary object to provide an improved construction of pickling tank of that type in which is employed a vertically reciprocable plunger, such plunger being designed for actuation to produce displacement of the pickling fluid in one part of the tank for effecting alternate increase and decrease of depth of such fluid in another communicating part which is utilized as a repository for the metal during the pickling thereof.

In structures of this character, the plunger operates within a fluid-displacement chamber between one of the side walls of the tank and a fixed partition wall which has its lower edge occupying spaced position relative to the tank bottom to provide a passage thereunder through which the pickling fluid may course back and forth between said displacement and pickling chambers of the tank. In such structures, as commonly employed, the plunger and the walls forming the guideway therefor are uniformly constructed of wood, rather than metal, because the use of wood timbers has been found much more practicable, due to the rapid deterioration of ordinary metals subjected to continued contact with the acids of the pickling bath.

However, due to the fact that wood timbers so employed also deteriorate more or less rapidly, becoming swollen and more or less distorted, especially at and adjacent to the ends of the timbers employed in the partition wall and plunger, free and unobstructed movement of the plunger in or through the displacement chamber may be maintained only for limited periods and at the expense of frequent repairs and replacements of parts, effected with considerable losses of time in the use of the tank. More specifically, the timber walls defining the fluid-displacement chamber and the timbers of the plunger become swollen, especially at the ends thereof, to the extent that, in reciprocations of the plunger, free movement is obstructed, resulting in the engaging surfaces of the plunger and the walls becoming torn and splintered. Furthermore, the exposed ends of the usual tie-

rods employed for securing together the various timbers of which the plunger and the partition wall are formed, as also the nuts carried by said rods, are rapidly corroded through contact with the acid bath to the extent that frequent renewals or replacements thereof are required.

It is the chief object of this invention to provide a pickling tank wherein the plunger ends and the adjacent portions of the walls forming the displacement chamber are firmly supported or held against distortion by metallic frame-like members which are specially resistant to the effects of the acid employed in the pickling bath, such members being employed to partially encase and sheath the ends of the plunger and the adjacent surfaces of the timber walls defining the displacement chamber, thereby to insure the preservation over relative long periods of time of a greatly improved working relation between said plunger and said displacement chamber walls; also to provide means for sheathing the ends of the tie rods and their attaching nuts in a manner preventing ready access thereto of the acids of the pickling bath, resulting in greatly prolonging the life of said parts.

In describing the invention in detail, reference is herein had to the accompanying drawings, in which—

Figure 1 is a transverse section of my improved pickling tank, showing my invention, the plunger being shown in end elevation;

Figure 2 is a view of a fragmentary portion of the tank and the plunger, partly in top plan and partly in section, the section being taken substantially on line 2—2, Fig. 1;

Figure 3 is an enlarged fragmentary detail section of the plunger taken substantially on line 3—3, Fig. 2;

Figure 4 is a lower edge elevation of a fragmentary portion of the plunger, showing a bolt-sheathing cap;

Figure 5 is a fragmentary detail section of the partition wall, taken substantially on line 5—5, Fig. 2;

Figure 6 is a lower edge elevation of a fragmentary portion of the division wall, showing a tie-rod sheathing cap;

Figures 7, 8 and 9 are enlarged views in side, edge and lower end elevations, respectively, of the metal sheath bands for the ends of the plunger; and—

5 Figures 10, 11 and 12 are similar views of the guide frame carried at each of the opposite ends of the fluid displacement chamber.

Referring to said drawings, 1 designates a side wall, 2 the opposite end walls, and 3 10 the bottom of a metal-pickling tank of a more or less common commercial type. Said tank has rigidly mounted therein parallel to and at a spaced distance from said side wall 1 a partition wall 4 which has its lower edge ele- 15 vated relative to the tank bottom to provide an unobstructed passageway thereunder for the pickling fluid between the metal pickling compartment or chamber 5 of the tank and the space 6 which is located intermediate the 20 wall 1 and said partition.

25 The space 6 constitutes a fluid displacement compartment or chamber in which a plunger 7 is vertically reciprocable for alternately displacing downwardly therefrom and permitting return thereto of the pickling solution contained by the tank, whereby is effected alternately the raising and lowering within the compartment 5 of the level of said solution for covering and partially uncover- 30 ing the metal articles to be treated, sloshing the acid pickling fluid over the surfaces of the sheets.

35 The partition wall 4, as are also the various walls of the tank, is formed, as ordinarily, of a plurality of heavy wood timbers 4^a disposed in closely superposed seated relation and firmly bound or tied together by means of a plurality of bolt-like tie rods 8 directed vertically therethrough, as shown. For 40 shielding the lower ends of said rods against exposure to the fluid or solution of the pickling bath, the said end of each is screwed within a threaded socket 9 provided therefor in a cap 10 which has an integral base 45 portion 10^a countersunk to an appropriate depth in the lower edge of the partition, as is clearly shown in Fig. 5, the outer dimensions of said base and the socket-like seat 11 provided therefor in said edge being in substantial 50 correspondence to afford a substantially fluid-tight joint, as shown in Figs. 5 and 6. As is manifest, said cap, countersunk as aforesaid, is effective for preventing access of the acid solution to the threads of the tie 55 rod. Said cap, which is constructed of an acid-resisting metal, is made of relatively great thickness to enable it to withstand the deteriorating effects of the acid over a long period of time.

60 Fitted within the opposite ends of the fluid displacement chamber 6 is a guide-frame, preferably made in the form of a casting of an acid-resistant metal, and comprising a back-plate 12 adapted to be mounted in a vertical position directly against the end wall

2 of the tank, and integral inwardly directed flanges 13 adapted to rest against the side wall 1 at one side and against the partition wall 4 at the other side. Each guide frame also includes an integral cap-plate 14 adapted for mounting in seated position upon the top of the adjacent end wall 2. The flanges 13 are suitably prolonged upwardly above the level of said cap-plate, forming extensions 13^a which have their upper ends flared outwardly 75 in opposite directions, as shown at 13^b, for facilitating entrance of the plunger 7 in the runway constituted by said back-plate 12 and the flanges 13.

Mounted in fixed embracing relation to the 80 plunger at each of the opposite ends of the latter is a band of acid resistant metal, preferably formed in a single piece, comprising parallel flat side members 15 designed, in reciprocations of the plunger, to operate against or 85 slide upon the flanges 13 hereinbefore referred to, as shown in Figs. 1 and 2, one or more cross members 16, and a transverse bottom member or plate 17 connecting the lower ends of said members 15. The upper ends of said members 15, as herein shown, are convergently inclined and occupy positions within recesses 18 provided therefor in the opposite sides of the plunger, and are secured to said plunger by 90 means of through bolts 19.

95 The bottom member 17 is of substantially rectangular plate form and has formed integral therewith downwardly projecting knobs 20, similar to the caps 10 hereinbefore described, which are socketed for the reception of the threaded lower ends of the end suspension rods 21 of the plunger, as shown. Tie rods 22 for the plunger are located intermediate said end suspension rods 21, as shown in Fig. 2, and socketed caps 23 countersunk in 100 the plunger have the threaded lower ends of said rods 22 received thereby, as shown in Figs. 3 and 4.

105 From the foregoing it will be understood that the guide frames interposed between the end portions of the partition wall 4 and the side wall 1 serve, first, as spacers whereby the width of the fluid displacement chamber at and adjacent to its ends is at all times uniformly maintained, and, second, as permanent 110 runway-forming guides for the plunger; also that the metal bands carried by the opposite ends of the plunger serve as sheaths for confining against undue swelling the timbers of the said plunger ends, thus to insure that said plunger shall at all times be substantially free 115 from binding engagement with the walls of the displacement chamber and, consequently, that the life of the plunger and the tank will be materially prolonged. Moreover, due to the sheathing of the threaded ends of the tie-rods and the suspension rods of the partition wall and the piston, respectively, by means of the caps 10, knobs 20 and caps 23, the expected 120 life of said rods is greatly increased.

What is claimed is—

1. In a pickling apparatus, the combination with a tank, of a wood partition wall located in parallel spaced relation to a side wall of the 5 tank and dividing the interior of the latter to form separate pickling and fluid displacement chambers, said wall having a passage thereunder through which fluid may course back and forth between said chambers, a metallic 10 guide frame rigidly mounted on said tank within each of the opposite ends of said displacement chamber and forming a runway, a plunger for vertical reciprocation in said displacement chamber, said plunger having its 15 ends at least partially encased and slidable within said runways.
2. In a pickling apparatus comprising a tank divided interiorly by a partition wall whereby are formed separate pickling and 20 fluid displacement chambers, said wall being formed of timbers arranged in superposed relation and having its lower edge spaced from the bottom of the tank to provide an avenue of communication between said chambers, a 25 metal guide frame fitted between said partition wall and the adjacent side wall of the tank at each end of said displacement chamber for relatively bracing said walls and forming a runway, a plunger reciprocable within said 30 displacement chamber, and metallic means embracing the ends of said plunger and slidable within said runways.
3. In a pickling apparatus comprising a tank divided interiorly by a partition wall 35 whereby are formed pickling and fluid displacement chambers, said wall being formed of timbers arranged in superposed relation and having its lower edge spaced from the bottom of the tank to provide an avenue of 40 communication between said chambers, a metal guide frame fitted between said partition wall and the adjacent side wall of the tank at each end of said displacement chamber for maintaining permanently the original 45 spacing of said walls and forming runways, a plunger reciprocable within said displacement chamber, and metallic sheath-like devices borne by and maintaining the integrity 50 of the ends of said plunger and rendering the latter freely shiftable along said runways.
4. In a pickling apparatus comprising a tank divided interiorly by a partition wall whereby are formed pickling and fluid displacement chambers, said wall being formed 55 of timbers arranged in superposed relation and having its lower edge spaced from the bottom of the tank to provide an avenue of communication between said chambers, a metal guide frame fitted between said partition 60 wall and the adjacent side wall of the tank at each end of said displacement chamber for maintaining permanently the original spacing of said walls and forming runways, a plunger reciprocable within said displacement 65 chamber, suspension rods for said
- plunger directed vertically through the latter, and metallic end sheathing devices for said plunger, said devices including a transverse member embodying sockets in which the lower ends of said suspension rods are 70 received.
5. In a pickling apparatus comprising a tank divided interiorly by a partition wall whereby are formed pickling and fluid displacement chambers, said wall being formed 75 of timbers arranged in superposed relation and having its lower edge spaced from the bottom of the tank to provide an avenue of communication between said chambers, said partition wall including tie rods directed 80 vertically through the timbers thereof, socketed caps countersunk within the lower edge of said wall and having the lower ends of said rods threaded therein and shielded thereby from liquid contents of the tank, a metal 85 guide frame fitted between said partition wall and the adjacent side wall of the tank at each end of said displacement chamber for relatively bracing said walls and forming a runway, a plunger reciprocable within said 90 displacement chamber, and metallic means embracing the ends of said plunger and slidable within said runways.
6. In a pickling apparatus comprising a tank divided interiorly by a partition wall 95 whereby are formed pickling and fluid displacement chambers, said wall being formed of timbers arranged in superposed relation and having its lower edge spaced from the bottom of the tank to provide an avenue of communication between said chambers, said partition wall including tie rods directed 100 vertically through the timbers thereof, socketed caps countersunk within the lower edge of said wall and having the lower ends of said rods threaded therein and shielded thereby from liquid contents of the tank, a plunger reciprocable within said displacement chamber, rods extending vertically through said 105 plunger, and cap-like means receiving the lower ends of said rods and whereby said ends are shielded against contact therewith 110 of fluid contents of the tank.
7. In a pickling apparatus comprising a tank divided interiorly by a partition wall 115 whereby are formed pickling and fluid displacement chambers, said wall being formed of timbers arranged in superposed relation and having its lower edge spaced from the bottom of the tank to provide an avenue of communication between said chambers, said partition wall including tie rods directed 120 vertically through the timbers thereof, socketed caps countersunk within the lower edge of said wall and having the lower ends of said rods threaded therein and shielded thereby from liquid contents of the tank, a plunger reciprocable within said displacement chamber, rods extending vertically through said 125 plunger, and cap-like means receiving 130

- the lower ends of said rods and whereby said ends are shielded against contact therewith of fluid contents of the tank, metal guide frames fitted within the opposite ends of said displacement chamber and forming runways for the ends of said plunger, and metallic means at least partially sheathing said ends of the plunger and freely slidable within said runways.
- 10 8. In a pickling apparatus comprising a tank divided interiorly by a partition wall whereby are formed pickling and fluid displacement chambers, said wall being formed of timbers arranged in superposed relation and having its lower edge spaced from the bottom of the tank to provide an avenue of communication between said chambers, said partition wall including tie rods directed vertically through the timbers thereof, a plunger embodying superposed timbers and rods directed vertically through said timbers, socketed cap-like members receiving and shielding the lower ends of said rods, and co-operating metal guide members carried by each of the opposite ends of said plunger and by the tank at opposite ends of said displacement chamber whereby a free working relation is maintained between said ends of the plunger and the ends of said chamber.
- 20 25 30 In testimony whereof, I affix my signature.
CHARLES SHRIVER.
